(57) CLAIM

The ornamental design for a gift wrapping bag, as shown and described.

DESCRIPTION

FIG. 1 is a perspective view of the gift wrapping bag of the present invention;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is an environmental perspective view thereof, illustrating a gift inserted into the gift wrapping bag; and, FIG. 9 is an environmental perspective view thereof, illustrating a gift inserted into the gift wrapping bag and the top of the bag in a closed position.

The portions of the gift wrapping bag illustrated in broken lines form no part of the claimed subject matter.
